UNITED STATES PATENT OFFICE.

CARL HEINRICH FLORENZ MÜLLER, OF HAMBURG, GERMANY.

X-RAY TUBE.

SPECIFICATION forming part of Letters Patent No. 772,667, dated October 18, 1904.

Application filed March 23, 1904. Serial No. 199,649. (No model.)

To all whom it may concern:

Be it known that I, CARL HEINRICH FLORENZ MÜLLER, a subject of the German Emperor, and a resident of Hamburg, in the German Empire, have invented certain new and useful Improvements in X-Ray Tubes, of which the following is a specification.

My invention relates to improvements in Roentgen tubes, and more particularly to means for adjusting and regulating the intensity of the rays generated in and emanating from the tube. As is well known, this object may be accomplished more or less effectively by regulating the degree of vacuum in the tube; but I have found that the penetrating power and volume of rays desired to be obtained from a tube can be most effectively controlled and regulated by varying the area of the reflecting-surface of the cathode. In my present invention I have shown a structure wherein this object can be accomplished, and I have also found that the two methods of regulation above referred to can be combined very readily and to great advantage, the result being a tube which is entirely under the control of the operator and one capable of a very wide range of adjustment and utility.

One form of my invention is shown in the accompanying drawings, wherein—

30 Figure 1 is a longitudinal section through a Roentgen tube in accordance with this invention, and Fig. 2 is a detached view of the adjustable cathode in another operative condition.

35 Similar letters of reference are employed to designate like parts in the two figures.

The Roentgen tube *a* is provided in the known manner with a principal and also a subsidiary anode *b* and *c*, respectively. The 40 fore portion of the cathode is composed of an inner concave mirror *f'* and an outer annular body *f''*, these parts forming a large reflecting-surface toward the anticathode *b* when the inner hollow mirror is situated in 45 the position shown in Fig. 1—that is to say, in the annular body.

The annular body *f''* is fixed upon a tube *h*, of insulating material, which surrounds the metallic sleeve *h* and bears upon it. The piston-rod *g*, carrying the concave mirror *f'*, is

displaceably mounted in the sleeve *h*. The annular body *f''* is therefore insulated from the conductor *i* *h* by means of the insulating-tube *h*, and the current can only enter the annular body when the concave mirror *f'* is in contact with the same—that is to say, when it occupies the position shown in Fig. 1. In this case the parts act as a single cathode of large size. On the other hand, when the inner concave mirror is pushed out—that is to say, when it is removed from contact with the annular body *f''*, Fig. 2—only the concave mirror *f'* is operative, because the annular body *f''* is then without current.

When the parts of the cathode are in the position shown in Fig. 1, the reflecting-surface is of comparatively large size and rays in large volume are emitted. When the parts are in the position shown in Fig. 2, the effective reflecting-surface is greatly reduced and the rays emitted are correspondingly reduced. It will also be seen that by making the cathode-reflector movable its distance from the anticathode may be regulated, and in this manner it is possible to so arrange the parts that the point of focus corresponds with the surface of the anticathode, and it will be understood that the intensity of the rays may in this manner be regulated to some extent.

The displacement of the concave mirror *f'* or of the piston *g*, carrying it, in the sleeve *h*, is effected by suitably inclining and shaking the Roentgen tube. The piston *g* is therefore mounted in the sleeve *h* with such friction that it will remain in the position in which it has been set. For the purpose of finer adjustment of its degree of hardness the Roentgen tube is also preferably provided with an auxiliary cathode *d*, which is arranged in a chamber *e*, fused directly on the sphere *a*, this cathode *d* carrying on its inner end a gas-producing body *l* (such as a disk of mica, for example) and serving in the known manner for rendering the tube softer. In the same vacuous space with the main cathode I also arrange a secondary terminal, which consists of a platinum wire or some other similar substance and which when heated by the passage of an electric current or otherwise has the property of absorbing the gaseous matter within the tube,

thereby enabling the operator to raise the vacuum and harden the tube when the same may be necessary. The arrangement of the two last-described regulating devices in chambers which are quite separate one from the other and which proceed directly from the sphere *a*, contrary to what has hitherto been the usual arrangement of them in a common chamber or in a chamber divided by a partition, presents the advantage that, first, the tube as a whole is reduced in volume, and, second, the rays proceeding from one electrode are not able to influence the substance of the other, which would prejudicially affect the regulation sought to be attained.

Having fully described my invention, what I claim, and desire to secure by Letters Patent, is—

1. A vacuum-tube having anode and cathode terminals, a primary regulator for varying the intensity of the cathode rays and a secondary regulator for controlling the degree of vacuum of the said tube, substantially as described.

2. A vacuum-tube having anode and cathode terminals located therein, and means for varying the reflecting-surface of the cathode-terminal, whereby the intensity of the rays is controlled and regulated, substantially as described.

3. A vacuum-tube having anode and cathode terminals located therein, said cathode being provided with a variable reflecting-surface for regulating the intensity of the rays, and a secondary regulator comprising means for varying the degree of vacuum in the tube, substantially as described.

4. A vacuum-tube having anode and cathode terminals located therein, said cathode-terminal comprising a plurality of separable reflecting-surfaces insulated from each other when separated, substantially as described.

5. In a vacuum-tube for generating X-rays, a cathode-terminal comprising a reflecting-surface composed of a plurality of concentric separable parts, said parts being electrically insulated one from another when out of physical contact, substantially as described.

6. A regulator for varying the intensity of rays in a vacuum-tube, comprising a cathode-terminal having a reflecting-surface composed of a plurality of parts insulated from one another when out of contact, a portion of

said reflecting-surface being movable so as to vary the distance between it and the anticathode in the tube, substantially as described. 55

7. In a vacuum-tube, the combination of a set of terminals located in said tube, one of said terminals having a variable reflecting-surface for changing the intensity of the rays issuing from the tube, substantially as described. 60

8. In a vacuum-tube, the combination of a set of terminals located in said tube, one of said terminals having a reflecting-surface, a portion of which may be rendered inoperative 65 to change the intensity of the rays issuing from the tube, substantially as described.

9. In a vacuum-tube, the combination of a set of terminals located in said tube, one of said terminals having a fixed member and an 70 adjustable member coacting therewith to vary the intensity of the rays issuing from the tube, substantially as described.

10. In a vacuum-tube, the combination of a set of terminals located in said tube, one of 75 said terminals having a fixed member in circuit and coacting with an adjustable member, and means for disconnecting and rendering said fixed member inoperative to vary the intensity of the rays issuing from the tube, sub- 80 stantially as described.

11. In a vacuum-tube, the combination of a set of terminals located in said tube, one terminal comprising an annular member normally in circuit and coacting with a central 85 adjustable member, and means for adjusting said central member and disconnecting said annular member to vary the intensity of the rays issuing from the tube, substantially as described. 90

12. In a vacuum-tube, the combination of a set of terminals located in said tube, one terminal comprising an annular member mounted on an insulated support, and a central adjustable member normally registering and co- 95 acting with said annular member and slidably adjustable to vary the intensity of the rays issuing from the tube, substantially as described.
